HORN SPEAKER

William N. Herleman, Sycamore, Ill., and Richard G. Myrlan, Elkhart, Ind., assignors to The Wurlitzer Company, Chicago, Ill., a corporation of Ohio

Filed Feb. 20, 1967, Ser. No. 5,874

Term of patent 14 years

(Cl. D26—14)

FIG. 1 is a front perspective view of a horn speaker showing our new design;

FIG. 2 is a front elevation thereof;

FIG. 3 is a top plan view thereof; and

FIG. 4 is a fragmentary rear elevation thereof.

The dominant features of my design reside in the portions shown in full lines. The electric cord member is broken away to indicate indeterminate length.

We claim:

The ornamental design for a horn speaker, as shown and described.
